DESIGN FOR A LIGHTING FIXTURE

Ernest H. Greppin, Brighton, N. Y., assignor to
Wilmot Castle Company, Rochester, N. Y., a
corporation of New York

Application February 9, 1942, Serial No. 105,723

Term of patent 7 years

To all whom it may concern:

Be it known that I, Ernest H. Greppin, a citizen of the United States, residing at Brighton, in the county of Monroe and State of New York, have invented a new, original, and ornamental Design for a Lighting Fixture, of which the following is a specification, reference being had to the accompanying drawing, forming part thereof,

Fig. 1 is a side elevational view of a lighting fixture, showing my new design;

Fig. 2 is a vertical sectional view taken centrally through the same, and

Fig. 3 is a bottom plan view of the same.

I claim:

The ornamental design for a lighting fixture, substantially as shown.

ERNEST H. GREPPIN.
